UNITED STATES PATENT OFFICE

WILLIAM WALTER HUDSON, OF SALT LAKE CITY, UTAH

STOKER MOTOR CONTROL

Application filed April 3, 1931. Serial No. 527,604.

The invention relates to improvements in stokers of a general type in which the fuel is fed from a hopper to a fire pot, and in which combustion air is supplied to the fire by means of a blower, both the feeding means for the fuel, and the blower, or at least the latter, being driven by an electric motor. Heretofore, even when using a closure for the hopper provided with a filling door, there has been danger of back-blown dust and gas-laden air discharging from the door, finding its way to floors above and soiling furnishings, in addition to being a more or less dangerous element on account of the existing coal gas.

The air discharged from the blower is of course under some pressure and while most of this air rises through the fire and supports combustion, some of its blows rearwardly through the fuel-conducting means and consequently blows from the hopper upon opening of the door. It is the object of my invention however, to overcome this difficulty by the provision of unique means for automatically breaking the circuit of the blower-operating motor when the hopper door is opened. Thus, when re-filling the hopper or opening its door for other reason, there is no danger of allowing the escape of a large quantity of gas and dust-laden air.

With the foregoing in view, the invention resides in the novel subject matter herein-after described and claimed, description being accomplished by reference to the accompanying drawings.

Fig. 1 is a side elevation partly in section showing a stoker for a furnace, said stoker embodying my improvements.

Fig. 2 is a top plan view partly in horizontal section.

Fig. 3 is an enlarged vertical sectional view substantially on line 3—3 of Fig. 2, the door and the motor-stopping switch being shown open in dotted lines.

While one specific embodiment is herein illustrated, it is to be understood that within the scope of the invention as claimed, numerous variations may be made.

A stoker is shown embodying a hopper 4 having a fuel discharge pipe 5 leading to a

fuel pot or tuyère 6, the fuel being fed through said pipe 5 by a screw conveyor, a plunger or any other preferred means driven by an appropriate train of operating connections, from an electric motor 7. This motor also drives a blower 8 from which an air-conducting pipe 9 leads to an air jacket 10 around the fuel pot 6. From this jacket, the air escapes into the fuel as shown by the arrows in Fig. 1, most of the air ascending through the fire bed and supporting combustion, while some of it returns through the pipe 5 into the hopper 4. To prevent this back-blown air and the dust and gases entrained thereby, from discharging into the furnace room or the like, a closure 11 is provided for the upper end of said hopper. This closure embodies two top portions 12 and 13, both of which incline to a ridge 14. The portion 13 is provided with an inclined door 15 whose upper end is hinged at 16 on a line parallel with the ridge 14. A suitable latch 17 is provided for the door and when said latch is released and the door opened, the hopper may be refilled. Provision is made for automatically stopping the motor 7 whenever the door 15 is opened, preventing discharge of dust and gas-laden air at that time.

In the present showing, an ordinary knife switch 18 is mounted upon the top portion 12 of the hopper closure 11, said switch being embodied in the circuit of the electric motor 7. The base 19 of the switch is secured upon the top portion 12, and the contact-bridging blade 20 is inclined, the lower end of said blade being pivoted at 21 while its upper end 22 is spaced above the ridge 14. A suitable push link 23 is disposed over the door 15 and is inclined, the upper end of said link being pivoted to the upper end 22 of the switch blade 20, as denoted at 24. The lower end of the link 23 is pivoted at 25 to an upstanding bracket 26 which is secured to the door 15.

The switch and operating elements therefore, remain in the positions shown in full lines in Figs. 1, 2 and 3 under ordinary circumstances, but whenever the door 15 is opened as shown in dotted lines in Fig. 3, the link 23 pushes against the switch blade 20, thereby opening the switch and automatically

breaking the circuit of the motor 7 to stop the blower 8. It is thus insured that while the door stands open, no air, gas and dust can be blown from the hopper to cause trouble or 5 inconvenience in one way or another. As soon as the door 15 is again closed, the switch 18 becomes automatically closed also, again completing the circuit of the motor 7 so that the blower 8 continues to operate.

10 W on the drawings diagrammatically illustrates wiring for the motor, said wiring embodying the switch 18 and a main switch diagrammatically illustrated at S. Any other appropriate wiring could of course be 15 employed and the invention may be carried out with a switch of any appropriate design other than that shown. Then too, it will be understood that any desired part or parts may be insulated to confine the current travel 20 to the desired path.

I claim:—

1. In a stoker, a hopper having means for feeding fuel to a fire-pot, a blower having means for conducting combustion air to the 25 fire-pot, an electric motor for driving said blower, a closure for said hopper to normally prevent discharge of back-blown dust-laden air from said hopper, said closure embodying a normally closed door, a normally 30 closed switch embodied in the circuit of said motor, and means connecting said door with said switch for automatically opening said switch when said door is opened, thereby stopping the motor and blower and preventing 35 back-blowing of dust-laden air through the open door.

2. In a stoker, a hopper having means for feeding fuel to a fire-pot, a blower having means for conducting combustion air to the 40 fire-pot, an electric motor for driving said blower, a closure for said hopper to normally prevent discharge of back-blown dust-laden air from said hopper, said closure embodying a normally closed door, a normally closed 45 switch mounted on said closure and embodied in the circuit of said motor, and means connecting said door with said switch for automatically opening said switch when said door is opened, thereby stopping the motor and blower and preventing back-blowing of dust-laden air through the open door.

3. In a stoker, a hopper having means for feeding fuel to a fire-pot, a blower having means for conducting combustion air to the 55 fire-pot, an electric motor for driving said blower, a closure for said hopper to normally prevent discharge of back-blown dust-laden air from said hopper, said closure embodying two top portions both inclined to a 60 ridge, one of said top portions having an upwardly swingable door whose upper end is hinged on an axis parallel with said ridge, a switch embodied in the circuit of said motor and secured upon the other of said top portions, said switch having an inclined contact-

bridging blade whose lower end is pivoted and whose upper end is spaced above said ridge, an inclined push link over said door having its upper end pivoted to said upper end of said blade, and means establishing a 70 pivotal connection between the lower end of said link and said door for effecting automatic opening of the switch when the door is opened.

In testimony whereof I affix my signature. 75
WILLIAM WALTER HUDSON.
